ICE SPUR

Clarence L. Penney, Mason City, Iowa

Application December 13, 1949, Serial No. 132,719

3 Claims. (Cl. 36—61)

1

The present invention relates to improvements in anti-slipping and traction increasing devices, and in particular to an ice creeper having a surface engaging spur adapted to be worn on the shoe while walking or traveling on smooth slippery surfaces.

One object is to provide an anti-slipping and traction increasing device with an ice engaging spur which is adapted to be projected beyond the plane of the user's shoe sole and heel when traveling and walking over icy or smooth surfaces to prevent slipping and falling thereon.

Another object is to provide an anti-slipping and traction increasing device with an ice engaging spur which can be easily and conveniently retracted to an inoperative position when the user is walking on normal non-slipping surfaces in stores and public conveyances as well as other indoor surfaces.

Another object is to provide an anti-slipping and traction increasing device which can be readily applied to the shank of each shoe of the wearer and can be adjusted to fit shoes of various widths and sizes.

Another object is to provide an anti-slipping and traction increasing device which can be cheaply and economically manufactured by constructing the various parts of the frame structure from processed metal having portions stamped and cut to provide reinforcing corrugations, guide members for the spurs and various abutment surfaces.

Another object is to provide an anti-slipping and traction increasing device in which the spur or ice engaging prong is operated by a manual control member which can be conveniently manipulated by the wearer to project or retract the ice engaging spur depending upon the character of the surface over which the wearer is walking.

Another object is to provide an anti-slipping and traction increasing device in which the ice or surface engaging spur is controlled by a rotatable member so arranged that when said ice or other surface engaging spur is projected the upward force exerted on the rotatable member will be substantially in direct alignment with the axis of said rotatable member so that only a slight resistance to rotation of the rotatable member will prevent the same from being displaced from its operative position.

Another object is to provide a traction increasing and anti-slipping device which is formed of a frame structure having complementary corrugated portions to form mutually engaging sliding surfaces which hold the frame sections in aline-

2

ment and simultaneously reinforce the shank portion of said frame.

Other objects and advantages of the invention will become apparent during the course of the following description of the accompanying drawing wherein:

Figure 1 is a side elevational view of the traction increasing creeper showing the manner in which the same is applied to the shoe of the wearer, and illustrating the surface engaging spur in its projected position.

Figure 2 is a side elevational view similar to Figure 1, but showing portions of the frame and operating disc broken away and in section to illustrate various structural details, and illustrating the surface engaging spur in its retracted position.

Figure 3 is a vertical cross-sectional view taken on line 3—3 of Figure 1 looking in the direction of the arrows and illustrating various structural details of the frame structure and the manually controlled operating disc for projecting and retracting the surface engaging spur of the ice creeper, and

Figure 4 is a vertical cross-sectional view taken on line 4—4 of Figure 3 showing the manner in which the frame members are corrugated to form V-shaped mutually engaging interfitting and sliding surfaces.

In the drawing, and more in detail, there is shown for the purpose of convenience of illustration an ice creeper generally designated 5 which is adapted to be positioned at the shank of a conventional shoe illustrated in dotted lines in Figure 1.

The ice creeper and anti-slipping device 5 comprises a frame structure having angular frame members 6 and 7, each of which is formed with plate-like portions 8 and 9 respectively. The plate-like portions 8 and 9 are provided with reinforcing ribs 10 and 11 (Fig. 4) which, in addition to reinforcing the plate-like members 8 and 9, provides mutually engaging V-shaped sliding surfaces to hold the plate-like portions 8 and 9 in alignment when the angular frame sections 6 and 7 are adjusted relative to one another.

The plate-like members 8 and 9 of the respective frame sections are held together by adjusting screws 12 which extend through aligned slots 13 and 14 respectively of the plate-like members 8 and 9, and as illustrated in Figure 3, clamping nuts 15 are threaded on the screws 12 to hold the plate-like sections 8 and 9 in tight clamping engagement one with the other.

The angular frame section 6 is provided with

an upstanding portion 16 having a pair of spaced strap retaining loops 17 and 18 for accommodating heel and instep encircling straps C and D as illustrated in Figure 1 in dotted lines.

Similarly, the angle frame section 7 is formed with an upstanding wall 19 which is provided with strap receiving slots 20 and 21, which correspond in position to the strap receiving slots 17 and 18 in the angular frame section 6, and the ends of the straps C and D are similarly 10 looped through the slots 20 and 21 and are secured by buckles or other fastening means (not shown).

The angular frame section 7 is formed with an opening 23 in which there is received a disc-like actuating member 24 and said disc-like actuating member is stamped to provide an annular wall 25 which terminates in an annular flange 26. The annular wall 25 is adapted to be received within the opening 23 to provide a snug fit, but yet permit free rotation of the disc-like member 24 in a manner which will be herein-after more fully described.

Affixed to the inner face of the disc-like member 24 is a retaining disc 27 which is of a diameter slightly greater than the diameter of the opening 23 so that the peripheral edge will overlie the edge of the frame section 7 adjacent the opening 23. The clamping disc 27 is held in place by a screw 28 which extends through an opening in the actuating disc 24 and has its opposite end received in a correspondingly threaded opening in the retaining disc 27.

Formed integral with the annular flange 26 of the disc 24 is an extension 30 which extends tangentially, and is integrated with an arm 31 to reinforce the extension 30. The extension 30 is provided with an angular edge portion which terminates in a fingerpiece 32, and said angular edge portion is adapted to engage the upper edge 19 of the frame section 7 when the disc 24 is in one position. The upper portion 19 of the frame section 7 is offset as at 34 (Fig. 3) to provide a curved 90° portion 35. Thus, the angular flange 36 on the extension 30 may move freely through an angle of 90° and will not engage the upstanding wall portion 19 of the section 7.

The annular flange 26 is indented as at 39 for being alternately received in correspondingly shaped indented portions 40 and 41 of the frame section 7. Thus, the actuating disc 24 can be frictionally held in positions of a 90° angular displacement.

The plate-like section 9 is struck out as at 42 to provide an outwardly struck lug 43 which is adapted to provide a guide for an ice engaging prong or spur 44, the upper end of which is rounded as at 45 and is provided with an opening 46 for receiving a machine screw 47. The machine screw 47 is provided with an enlarged shank portion 48 and the inner end is reduced and threaded as at 49 for being received in a correspondingly threaded opening in the retaining disc 27. The enlarged shank portion 48 of the screw 47 passes through an opening 50 (Fig. 3) in the actuating disc 24. It will be noted, that the struck out lug 43 is provided with a passage 51 having oblique edge surfaces 52 to permit free sliding movement of the ice engaging prong or spur 44 when the same is projected or retracted, and it is to be noted that the lower end of the ice engaging spur is pointed as at 53 to penetrate the ice surface when the prong or spur is in its operative position.

In order to relieve the strain on the stud screw 47 the actuating disc 24 is pressed outwardly as at 54 to provide a protuberance having an arcuately curved surface 55 corresponding in shape to the rounded portion 45 of the ice pick or spur 44. Also, it will be noted that the ice engaging spur guide 43 is positioned such that the line of force will be slightly rearward of the dead center of the actuating disc 24, so that when walking, on ice or other smooth surfaces, the upward force applied to the ice engaging spur 44 will not cause angular displacement of the actuating disc 24.

In operation, the ice creeper 5 is attached to 15 the shank of a conventional shoe as shown in dotted lines in Figure 1 with the straps C and D likewise shown in dotted lines embracing the heel and instep portions of the foot respectively. Should the wearer desire to project the anti-slipping ice engaging spur 44 the fingerpiece 32 is angularly displaced 90° from the position shown in Figure 2 so that it assumes the position shown in Figure 1, with the ice spur projecting downwardly. With the ice spur in the position shown in Figure 1, the projection 39 will be received in the depression 41 and the actuating disc 24 will be frictionally held against angular displacement. If the wearer should desire to retract the ice engaging spur 44, the fingerpiece 32 is moved in a counter-clockwise direction from the position shown in Figure 1 to that shown in Figure 2. In this position, the projection 39 will be received in the depression 40 and the actuating disc 24 will be frictionally held in place with the ice engaging spur 44 retracted so that the lower pointed end 53 is above the plane of the sole and heel, S and H respectively, of the wearer's shoe.

It is to be noted that when the ice engaging spur 44 is projected, the pointed end 53 extends beyond the lower plane of the shoe heel and sole H and S a distance of approximately $\frac{1}{4}$ inch, and that by reason of the oblique edge surfaces 52 in the guide slot 51 the ice engaging spur 44 is held substantially rigid against movement in a lateral direction.

It is to be understood, that the form of the invention herewith shown and described is to be taken as a preferred embodiment thereof, and that various changes in the shape, size and arrangement of parts may be resorted to without departing from the spirit of the invention or the scope of the subjoined claims.

I claim:

1. In an anti-slipping device, a U-shaped frame adapted to be positioned beneath the shank portion of a shoe, said frame being formed of angular sections to provide upstanding side walls and overlapping plate portions, mutually engaging V-shaped ribs formed on said plate-like portions to reinforce the same and permit true sliding movement of said sections, bolt and slot connections for securing said plate-like sections in clamping engagement, a struck out lug formed on one of said sections having a guide opening, an ice engaging spur slidably mounted in said opening, a pressed metal disc-shaped actuator having an annular wall adapted to be rotatably received within an opening in one of said upstanding walls, a retaining disc secured to said actuator disc to hold the same within said opening, a pin carried by said actuating disc operatively connected to said spur and a finger engaging portion formed on said actuator disc to move the same 70 through an angular distance approximately 90°.

2. In an anti-slipping device, a U-shaped frame adapted to be positioned beneath the shank portion of a shoe, said frame being formed of angular sections to provide upstanding side walls and overlapping plate portions, mutually engaging V-shaped ribs formed on said plate-like portions to reinforce the same and permit true sliding movement of said sections, bolt and slot connections for securing said plate-like sections in clamping engagement, a struck out lug formed on one of said sections having a guide opening, an ice engaging spur slidably mounted in said opening, a pressed metal disc-shaped actuator having an annular wall adapted to be rotatably received within an opening in one of said upstanding walls, a retaining disc secured to said actuator disc to hold the same within said opening, a pin carried by said actuating disc operatively connected to said spur and a finger engaging portion formed on said actuator disc to move the same through an angular distance approximately 90°, said actuating disc being provided with a projection having an arcuately curved surface for engaging a correspondingly curved surface on the upper end of the ice engaging spur to provide an abutment therefor.

3. In an anti-slipping and traction increasing

device, a U-shaped frame adapted to be positioned beneath a shoe with the side walls of the frame extending upwardly on each side thereof, an ice engaging spur slidably supported by one of said side walls to slide to and fro to its projected and retracted position, an actuator disc rotatably mounted on said upstanding side wall having a radially extending fingerpiece, a pin carried by said disc operatively connecting the upper end of the spur to said disc, said spur being arranged in diametral alinement with said disc when in its projected position and friction means for holding said disc in positions of angular movement and displacement approximately 90° apart.
